Primary Examiner — Cynthia Underwood*(74) Attorney, Agent, or Firm* — Hamre, Schumann, Mueller & Larson, P.C.(57) **CLAIM**

The ornamental design for a cross strap case for electronic computer, as shown and described.

DESCRIPTION

FIG. 1 is a perspective view of a cross strap case for electronic computer;

FIG. 2 is a front view thereof;

FIG. 3 is a rear view thereof;

FIG. 4 is a left side thereof;

FIG. 5 is a right side thereof;

FIG. 6 is a top view thereof; and,

FIG. 7 is a bottom view thereof.

The broken lines shown in the Figures are for illustration purpose only and form no part of the claimed design.

1 Claim, 5 Drawing Sheets(56)
